TELEGRAPH REGENERATING SYSTEM

Marion H. Woodward, Arlington, Va., assignor, by
mesne assignments, to International Standard
Electric Corporation, New York, N. Y., a cor-
poration of Delaware

Application July 1, 1936, Serial No. 88,367

4 Claims. (Cl. 178—70)

The present invention relates to an improved regenerator circuit for re-shaping telegraph signals which are received from an incoming line with a certain amount of distortion, and repeating them to an outgoing line without distortion. More specifically this invention provides a re-shaping regenerating circuit for use with signals which are transmitted at a substantially constant rate, as from a tape transmitter or other constant speed transmitting device.

One of the principal features of this invention is the provision of an improved timing circuit for controlling the regenerating relays, this timing circuit comprising a self-energized tuning fork and a speed correcting circuit for maintaining the tuning fork in synchronism with the fundamental rate of signal transmission, generally referred to as the "center-hole speed".

It should be understood that in signal regenerating circuits used with signals of constant center-hole speed, it is usual to provide a timing arrangement adapted to operate substantially in synchronism with the center-hole speed of the received incoming signals and then to arrange the signal repeating or regenerating relays which retransmit the signal to the outgoing line so that they are controlled jointly by this timing mechanism and by the distorted incoming signals. The difficulty in the usual arrangements of this type has been to provide such a timing mechanism which will remain sufficiently accurately in synchronism with the average center-hole speed of the incoming signals and yet have such a uniformity of speed that the time pulses generated by it will not instantaneously vary in speed with the accidental variations of individual signal pulses.

According to the present invention a timing mechanism having the desired characteristics is provided, which has for its principal element a self-driven tuning fork. This self-driven tuning fork is then corrected in speed from time to time by a fork correcting circuit which forms one of the most important features of the invention.

One primary object of the present invention is to provide a fork correcting circuit for the purpose outlined above, as well as for other similar purposes, which shall maintain a high degree of synchronism between the fork and the average center-hole speed of an incoming signal and which shall yet be comparatively unaffected by the individual distortions of the signal pulses, especially with regard to that form of distortion generally known as characteristic distortion. Another primary object of the present invention is to provide such a fork correcting circuit which shall be adapted to readily cooperate with the type of automatic bias corrector described in United States Patent 1,929,879 to A. F. Connery. More specifically it is an object of this inven-

tion to provide a tuning fork timing device in which each correction performed by the fork corrector equipment shall alter the phase of the fork by a fixed predetermined amount in a fixed predetermined direction, the number of corrections occurring per minute being variable in accordance with the difference between the natural fork speed and the average center-hole speed of the incoming signals.

This invention is applicable to signals of the well known Baudot type and of the so-called submarine Morse type, as well as to other types of signals, provided only that these signals are characterized by some repeatedly recurring characteristic and are transmitted at a substantially constant speed. The specific embodiment in connection with which this invention is here described is adapted to operate with the so-called submarine Morse type of telegraphic signals in which three different types of impulses (positive, negative and zero) are employed, all pulses being of equal length.

The invention may best be understood by reference to the accompanying single figure of drawings which represents a regenerating repeater for reshaping and retransmitting submarine Morse signals, this repeater having a fork-controlled timer in accordance with the invention. It will be observed that in this drawing there are shown a number of polarized relays each having two or more windings. For simplicity in reading the drawing these windings have been so arranged that in every case a current whose conventional direction of flow is from right to left through any of the windings will tend to move the contact tongue of its relay from right to left. Similarly a current flowing from left to right through any winding of any polarized relay in the drawing will tend to move the associated relay tongue from left to right.

The invention may be best understood by reference to the accompanying single figure of drawings which represents a regenerative repeater for submarine Morse signals having a fork controlled timer in accordance with the present invention.

Referring now to the drawing, 1 represents the incoming signal cable and 2 is a polarized cable receiving relay of the moving coil type. It is assumed that this relay will be actuated by the incoming signals in the usual manner, the signals originally coming from an automatic cable transmission in the usual form. When a dot signal is received the tongue of relay 2 will make with its dot contact whereas a dash signal will cause it to make with its dash contact. A zero or no current signal will cause the tongue to return to or remain in its central position making neither contact. Under control of the contacts of relay 2, locking relays 3 and 4 are operated in accordance with the position of the tongue of

relay 2. Under control of these last named relays 3 and 4 the transmitting relays 5 and 6 are operated to transmit to the outgoing cable 7 regenerated signals corresponding to the distorted signals received in cable 1. Thus the principal chain of apparatus for regenerating signals between cables 1 and 7 consists of relay 2, relays 3 and 4 and finally relays 5 and 6 in the order named.

10 In order to eliminate the distortion in the signals the operation of the transmitting relays 5 and 6 is controlled not only by the chain of regenerating apparatus above described but also jointly by the special timing equipment which is a 15 particular feature of the present invention. This timing equipment is shown inside of the dot and dash rectangle in the drawing and its exact action will be fully explained below. Briefly, however, the function of this timing equipment is to 20 intermittently connect ground to wire 8 in synchronism with the average center-hole speed of the incoming signals. It will be noted that the circuits through transmitting relays 5 and 6, although they are prepared by the operation of 25 relays 3 and 4 under control of the moving coil cable relay 2 are not completed until ground is connected to wire 8 by the timing device. The result of this arrangement is that the transmitting relays 5 and 6 will remain in the position 30 previously taken until the instant when the timing device places the pulse of ground on wire 8. Then at this instant the transmitting relays will shift to the new positions determined by the positions occupied at that time by the locking relays 35 3 and 4.

Referring more particularly to the timing arrangement, relay 9 is a corrector relay adapted to be operated by either of two windings 10 and 11, which are connected in series with the locking 40 relays 3 and 4. This relay 9 is preferably of the two-position polarized type for the sake of speed and sensitivity and is electrically biased by an auxiliary winding 12 so that in the absence of current through its operating windings it will return to its spacing contact S as shown in the figure. The tongue of relay 9 is connected to positive battery through condenser 13 so that upon motion of this tongue against its marking 45 contact M a momentary surge of charging current will flow through the condenser and the relay contacts, thence through one or more windings of relay 14, through the tongue of relay 15 to ground. Resistor 18 is connected to the normal or spacing contact of the corrector relay 9 to 50 discharge condenser 13 each time this relay returns to normal so as to prepare for another surge of charging current upon the next operation of this relay. It will be noted that if relay 15 is in its normal position with its tongue resting against its spacing contact the path for the above mentioned charging current extends through both windings 16 and 17 of relay 14. These windings are so balanced that in this case relay 14 will not tend to operate. If, however, relay 15 is in its 55 energized position with its tongue resting against its marking contact M, the path for said charging current extends only through winding 16 so that in this condition the charging current will energize the auxiliary correction relay 14. This auxiliary corrector relay is also of the two-position polarized type and is electrically biased by means of winding 31 so that its tongue normally rests against its spacing contact.

The principal stabilizing element of the timing mechanism consists of fork 19 self-driven by

magnet 20 through back contact 21. This fork is normally adjusted to vibrate at a rate slightly faster than the average center-hole speed of the incoming signals. Cooperating with this fork is contact 23 which serves to control the operation of relay 15 through condenser 24 in shunt with the leak resistor 25. By proper proportioning of condenser 24 and resistor 25 the length of time during which relay 15 is in its operated position, as well as the amount of delay between the closure of contact 23 and the operation of relay 15 10 may be adjusted. Thus, by proper adjustment of relay 15, resistor 25 and condenser 24, the tongue of relay 15 is caused to close against its marking contact once for each cycle of the fork, 15 the duration of these closures and their phase relative to the fork cycle being adjustable within certain limits.

It should now be seen that the equipment thus far described in the timing mechanism is in general based upon two independently actuated mechanisms (tuning fork 19 and corrector relay 9) one of which has a natural period determined by the mechanical characteristics of the fork and the other of which is controlled from the incoming signal. Jointly under the control of these two mechanisms is auxiliary corrector relay 14 which, as above described, is adapted to operate upon the energization of relay 9 only if such energization coincides with a closure of the marking 30 contact of the fork-controlled relay 15.

Under control of this auxiliary corrector relay 14 there are provided correcting circuits and equipment for delaying the phase of the tuning fork as follows: Correcting relay 26 is connected 35 to the marking contact of relay 14 so as to be energized by the operation of the latter. Also connected to this same marking contact is locking winding 27 of the relay 14 itself in series with a resistor 28. Slow release relay 29, on the other 40 hand, is connected to the normal or spacing contact of relay 14. Thus, upon the energization of relay 14 correcting relay 26 will be operated. relay 14 itself will be locked and slow release relay 29 will commence to deenergize. This in turn will 45 then cause the release of relay 14 and then of relay 26, while relay 29 will be reenergized in preparation for another release. Thus, it will be seen that upon each energization of relay 14 correcting relay 26 will become actuated and will remain in 50 its actuated position for a fixed predetermined time. The marking contact of relay 26 is connected so as to apply ground potential through a variable resistor 30 directly to the driving magnet 20 of fork 19. Since the circuit for this ground potential is independent of the back contact 21 of the fork, the result of the operation of relay 26 will be to superpose upon the intermittent driving current through magnet 20 a continuous current of adjustable value. Because of the characteristics of the fork and the normal amplitude at which it is operated the result of such a continuous energization will be not only to decrease the amplitude of the fork slightly but also to slow 55 down its rate of vibration. Since each operation of relay 26 lasts for a predetermined interval the total effect of each such operation will be to set the fork back in phase by a predetermined amount (preferably of the order of $\frac{1}{30}$ of a center hole). 60 The spacing contact of relay 29 is arranged to short circuit the above named locking winding 27 upon release of relay 29. This latter relay can be 65 adjusted to have any desired amount of delay in releasing by adjustment of its armature tensions 70 75

and travel, as well as by varying the volume and shape of the well known eddy current sleeves which are provided in relays of this type.

The above description of apparatus and their circuit relationships when taken together with the drawing should almost suffice to make clear how the equipment operates. For completeness, however, the following general description of the method of operation will be given.

It will be assumed that distorted signals are being received over cable 1 by moving coil relay 2 and it will be assumed that fork 19 is vibrating substantially in synchronism with the average center hole speed of these signals, the closures of contact 22 occurring roughly at the same time as the center of each signal element. The fork 19, however, is vibrating slightly more rapidly than the center hole speed of the incoming signals so that over a period of time the phase of the fork is gradually advancing with respect to the signal. Under control of the contacts of the moving coil relay 2, corrector relay 9 is intermittently operated, this relay 9 operating upon each closure of the dash or dot contact of relay 2.

It should be noted that the corrector relay will not operate in response to each element of the received signal but only in response to certain ones of these elements since a zero or no current pulse will never actuate the corrector relay, and since a dash or dot pulse preceded by a similar pulse will not actuate this relay but merely hold it operative.

If, for example, the incoming signal consists of the message ON DX (which would be represented by the elements (1) minus (2) minus (3) minus (4) zero (5) minus (6) plus (7) zero (8) zero (9) zero (10) minus (11) plus (12) plus (13) zero (14) minus (15) plus (16) plus (17) minus) relay 9 would be actuated only by the first, fifth, sixth, tenth, eleventh, fourteenth, fifteenth and seventeenth pulses. The relay will, of course, remain operated during the second, third, twelfth and sixteenth pulses but will not reoperate upon these pulses. Because of the fact that condenser 13 charges almost immediately after the tongue of relay 9 strikes its marking contact the continued energization of this relay 9 will be ineffective and current will flow through the windings of relay 14 only when relay 9 moves from its unoperated state to its operated state.

At the same time that corrector relay 9 is intermittently operating under the control of the signal as above described, relay 15 is being regularly operated under control of the fork contact 23. The adjustment of this relay 15 and of the resistor and condenser 24 and 25 which determine its operating characteristics are such that relay 15 will not operate until after the tongue of relay 9 has closed against its marking contact and condenser 13 has substantially finished charging. This statement is of course based on the assumption that the fork happens now to be in synchronism with the signal so that the closure of contacts 22 and 23 takes place approximately during the center of a signal pulse. Under these conditions, therefore, relay 14 will not become energized and no correction will be applied to the fork.

As the fork gradually advances in phase, however, with respect to the signal it will finally occur that the tongue of relay 15 closes against its marking contact before the charging of condenser 13 is finished. In this case relay 14 will be energized through its winding 16 and will immediately lock itself through its winding 27 and

also energize correcting relay 26 to slow down the vibrations of the fork. The correction applied to the fork by relay 26 will continue for a certain length of time determined by the characteristics of slow release relay 29 and will finally be terminated when the dropping of this slow release relay unlocks relay 14 (by short circuiting its winding 27) which then releases relay 26.

It will be noted that the above described correcting action will take place at the first opportunity each time the fork has advanced in phase with respect to the signal by more than a tolerated amount. The opportunities for correction will not occur at every signal pulse since relay 9, as above described, will become actuated only at certain points in the signal. In the case of the message above chosen, for example, the only points at which correction could possibly take place would be on the first, fifth, sixth, tenth, eleventh, fourteenth, fifteenth and seventeenth signal elements. But in all normal messages opportunities for correction will occur more than sufficiently often to maintain a satisfactory synchronism.

One of the important advantages of this correcting system is that it is always controlled by a certain part of the signal pulse, namely, the beginning of the pulse. Another very important feature is that this control is for the most part effected by those signal pulses which are unusually retarded with respect to the average center-hole phase of the signals.

It is well known that as a result of the characteristics of long lines a positive pulse which immediately follows a negative pulse or a negative pulse which immediately follows a positive pulse is more retarded during transmission than the average signal element. In the case of the particular message above chosen for illustration, such pulses as sixth, eleventh, fifteenth and seventeenth, for example, will be markedly late in arriving. On the other hand, such a pulse as the fifth one will be slightly early; such a pulse as the fourteenth one will be slightly late; and a pulse such as the first or tenth will be substantially normal.

Under ordinary operating conditions since the fork advances in phase only very slowly with respect to the signal the corrections will be nearly all controlled by the late pulses, such as the sixth, eleventh, fifteenth and seventeenth. This fact is of great value in reducing the drift of fork phase with respect to signal phase and is also of primary importance in making the system adaptable for use with the bias corrector described in United States Patent 1,929,879. Furthermore, it is a very great advantage of the present invention that the corrections applied to the fork are always of a fixed strength and endure for a fixed time, thus, resulting in setting back the phase of the fork by an amount which is independent of the instantaneous distortion of the signal used for correction.

The operation of the actual signal regenerating or repeating relays 3, 4, 5 and 6 is very nearly self-explanatory and need only briefly be outlined.

Upon the reception of a dash or dot the corresponding relay 3 or 4 is energized in an obvious manner. Such operation prepares operating circuits for the corresponding transmitting relays 5 and 6. At about the time corresponding to the center of the received signal pulse (or a short time thereafter to allow for relay operations) when it can be assumed that the correct locking

relay has been operated, contact 22 of fork 19 closes. This closure completes the circuit prepared by the locking relay so as to cause the transmitting relays at this moment to take up positions corresponding to the locking relays which control them. With respect to the outgoing cable this moment is the start of a new pulse. During the period that contact 22 is closed the locking relays are prevented from 5 altering their position by windings 32, 33, 34 and 35, the appropriate ones of which are at this time connected in series with the transmitting relays and with the fork contact 22. When the tongue of relay 2 leaves its dot or dash contact, or upon 10 the opening of contact 22 (whichever is later) the locking relays 3 and 4 will return to normal; but the transmitting relays will remain in the position in which they have been set until the next closure of fork contact 22.

20 It will thus be seen that the pulses sent out over the outgoing cable are governed in character by the center portions of the incoming pulses, which portions of course are the least likely to be erroneous. The timing, however, of 25 these outgoing signals will be wholly controlled by contact 22 of tuning fork 19 so that a uniform spacing of the outgoing signals is obtained.

With regard to the patented bias corrector above referred to, the application of this bias 30 corrector to the present regenerating system can be carried out in almost exactly the manner described in that patent for applying the bias corrector to a rotary regenerating system. It is merely necessary to insert in wires BC₁ and BC₂ 35 the two operating windings of a four-winding relay BC (corresponding to relay 11 of the above mentioned patent) whose tongue will close with its marking or spacing contact in accordance with whether the dot or dash contact of relay 2 40 is closed. Then an extra marking contact may be applied to relay 26 (corresponding to the marking contact of relay 17 in the above mentioned patent) for the purpose of sending out a pulse of positive polarity each time a correction 45 is made upon the fork. The extra marking contact of this relay 26 is then connected to the tongue of relay BC, and the marking and spacing contacts of this relay BC are connected through suitable locking windings of the relay 50 itself to the automatic bias corrector magnets (designated 33 and 34 in the above mentioned patent). Since the correcting steps in a structure of the present system are closely analogous to those of the rotary regenerator system for 55 which the above mentioned bias corrector was designed, this bias corrector will operate satisfactorily without modification. The output current of the bias corrector can be applied to the polarized moving coil cable relay 2 exactly as 60 illustrated and described in the above mentioned patent.

Although the preferred embodiment of the present invention is described and illustrated as having a fork which runs faster than the center-hole speed of the signals and is then corrected from time to time by retarding the fork, the converse arrangement can also be used in which the fork is normally slow and the corrections serve to accelerate it. In all cases, however, it is preferred to correct only in one direction (retarding or accelerating) and to apply each correction at a predetermined strength for a predetermined length of time. Preferably the duration of each

correction should be of the order of five to fifteen center holes, since an unduly long correction period precludes the possibility of frequent corrections and an unduly short period necessitates such a strong correction that the smooth vibration of the fork is disturbed. For signals of the rate ordinarily used in submarine cables, it has been found advisable to adjust the strength and duration of each correction so as to set the fork back approximately $\frac{1}{30}$ of a center hole in phase, 10 and to make the fork speed exceed the signal speed by such an amount that approximately 20 or 30 corrections per minute will take place.

What I claim is:

1. A signal regenerating telegraph repeater 15 comprising an incoming relay, a vibratory timing device, a signal retransmitting relay and connections for controlling the position of said retransmitting relay from said incoming relay and for controlling the exact time at which such position shall become effective from said vibratory timing device, in combination with corrector means for determining the phase difference between the motions of said incoming relay and said vibratory device and correcting means having a predetermined interval of operation, controlled by said corrector means for applying to said vibratory device a phase correction of fixed amount.

2. A signal re-shaping telegraph repeating 30 system comprising a receiving relay, a retransmitting relay, a vibratory timer, connections for controlling the operation of said retransmitting relay jointly from said receiving relay and said timer, and phase correcting means having a pre-determined interval of operation, controlled by said timer and the received signals for altering the phase of said timer by a given amount in a given direction in response to a phase difference between said timer and said receiving relay exceeding a certain value.

3. A telegraphic signal regenerating system comprising a receiving relay, a vibratory timing member, a transmitting relay jointly controlled by said receiving relay and said vibratory member, together with a variable delay determining device, a corrector relay operated with said receiving relay, means for correcting the speed of the fork in response to a difference in the time interval between the fork vibration and the operation of the corrector relay differs in one pre-determined sense from the time interval determined by said variable delay device and a second variable delay device, for determining the interval of operation of said correcting means.

4. A telegraphic signal regenerating system comprising a receiving relay, a vibratory timing member, a transmitting relay jointly controlled by said receiving relay and said vibratory member, together with a variable delay determining device, correcting means operable only when the time interval between the fork vibration and the operation of the receiving relay differs in a given sense from the time interval determined by said variable delay device, a second variable delay determining device operative in response to operation of said correcting means, a speed changing magnet for said member and means responsive to the operation of said second variable delay determining device for changing the speed of said vibratory member for an interval determined by said second variable delay device.

MARION H. WOODWARD.
